UNITED STATES PATENT OFFICE

2,074,931

DISPENSING CONTAINER

Earl F. Metcalfe, Cincinnati, Ohio, assignor to
 The General Pharmacal Company, Cincinnati,
 Ohio, a corporation of Ohio

Application May 10, 1935, Serial No. 20,824

6 Claims. (Cl. 221—95)

My invention relates to dispensing containers and particularly to a dispensing container in which a measuring chamber is associated with the dispensing opening.

5 It is an object of my invention to provide a dispensing container which can be inexpensively manufactured and in which, due to the manipulation of the cap members of the container, a measured charge may be dispensed.

10 Another object of my invention is the provision of a dispensing container in which the manipulation of the can top to measure a certain charge of the material within the container may be simply made, and in which the mechanical features of construction are such that there 15 is substantially no likelihood of the dispensing apparatus getting out of order.

Another object of my invention is the provision of dispensing mechanism in association with 20 a can closure which will be neat and attractive in appearance and sufficiently simple in construction that its operation will be readily understood by anyone with normal intelligence.

25 A further object of my invention is the provision of a dispensing container in which the dispensing apparatus may be manipulated without the necessity of other manipulation than a simple turning of an external cap member associated with the discharge opening in the container.

30 The objects to which I have referred and other objects which will appear in the following description I accomplish by that certain combination and arrangement of parts of which I have 35 illustrated a preferred embodiment. Referring to the drawing

Figure 1 is a perspective view with cutaway parts revealing the internal construction of the dispensing apparatus.

40 Figure 2 is a plan view of the container with the cover or closure member removed and with the dispensing apparatus moved to a position in which the dispensing opening is operative.

45 Figure 3 is a plan view similar to that of Figure 2 with the dispensing apparatus manipulated so that the dispensing opening into the measuring chamber is closed.

50 I have illustrated a circular container 1 formed preferably from sheet metal such as tin and with a bottom wall 2 crimped into place to form a permanent closure for the bottom of the container.

55 At the top of the container as illustrated, there is an annular tapered portion 3 open at the top and with a shoulder 4 formed at the base to limit

the frictional engagement thereon of one of the cap members which form a cooperating part of the dispensing apparatus. An internal cap 5 fits frictionally on the tapered annular portion 3. The internal cap has outwardly projecting 5 ribs 6 which register with an outwardly formed annular portion 7 in an external cap member 8.

For purposes of convenience in the manufacture of the external cap member I have shown 10 a two-part cap formed of the annular member 8 and an external cap member 9 which as indicated at 10 frictionally fits exteriorly of the annular member 8. The members 8 and 9 can, 15 however, be formed from a single piece.

The cap member 9 has a neck 11 threaded as 15 indicated to receive a closure member 12 having a threaded portion which engages the threaded portion of the neck.

Within the neck the measuring chamber 13 is 20 formed which, for purposes of illustration may be considered to have sufficient capacity to contain one teaspoonful of the ingredients of the container.

The cap member 8 has a semi-circular cut-away portion 14 through which material will 25 flow, when the can is inverted into the measuring chamber. The internal cap member also has a stop 15 which may, as indicated, be formed up from the metal.

The external cap member 8 also has a semi-circular opening 16 therein which in certain positions of the external cap member will register with the semi-circular opening 14 in the internal cap member 5.

In manipulating the measuring compartment 35 the person who wishes to measure out, for example a teaspoonful of medicine from the can turns the cap 9 including the annular portion 7 thereof in a clockwise direction as illustrated. This causes the edge of the opening 16 to contact the stop member 15 and limit the rotary movement of the external cap. The can is then inverted and while inverted the external cap member 9 is again rotated through a half circle in a clockwise direction which causes the solid wall portion 17 of the annular external cap portion 8 to close the opening with a charge to be dispensed retained within the measuring chamber 13 in the neck of the composite cap. The threaded closure member 12 is then unscrewed and the measured charge of the material may be poured into water or otherwise suitably dispensed.

Having thus described my invention, what I claim as new and desire to secure by Letters Patent, is:—

25

30

35

40

45

50

55

1. A container having associated with the discharge portion thereof a measuring chamber, said container having a round internal cap frictionally received on an open round walled end 5 of the container and having a dispensing opening therein, a round external cap member fitting on said internal cap member and also having a dispensing opening, said caps provided with cooperating means to permit rotary but non- removable movement of the external cap on the 10 internal cap, said external cap having a neck containing a measuring chamber and a discharge portion provided with a closure chamber, and means for limiting the rotary movement 15 of the external cap on the internal cap with the openings in registered and non-registered closed position.

2. A container having associated with the discharge portion thereof a measuring chamber, 20 said container having a round internal cap frictionally received on an open round walled end of the container and having a dispensing opening therein, a round external cap member fitting on said internal cap member and also having a dispensing opening, said caps provided with cooperating means to permit rotary but non-removable movement of the external cap on the internal cap, said external cap having a neck containing a measuring chamber and a 25 discharge portion provided with a closure chamber, and means for limiting the rotary movement of the external cap on the internal cap with the openings in registered and non- registered closed position, said means comprising 30 a lug extending from said internal cap adapted to abut the edges of the cap surrounding the opening in the external cap at its rotary limits of movement.

3. In combination with a container, dispens- 35 ing and measuring mechanism associated therewith comprising a cap member having a neck

provided with a screw cap, and means for dis- charging material from said container to fill the space within said neck upon screwing up of said cap.

4. A container having associated with the discharge portion thereof a measuring chamber, 5 said container having a round internal cap frictionally received on an open round walled end of the container and having a dispensing opening therein, a round external cap member fitting on said internal cap member and also having a dispensing opening, said caps provided with cooperating means to permit rotary but non-removable movement of the external cap on the internal cap, said external cap having a neck containing a measuring chamber and a discharge portion provided with a closure chamber, and means for indicating the open and 10 closed positions of the external cap on the internal cap.

5. A dispensing container having a neck, a measuring compartment within said neck pro- 15 vided with a screw cap, and valve means for permitting the flow of a measured quantity of material from said container into said compartment when said container is supported in inverted position, and means opening said valve when said cap is being screwed on, and closing said valve when said cap is being unscrewed.

6. A dispensing container having a neck, a measuring compartment within said neck pro- 20 vided with a screw cap, and valve means for permitting the flow of a measured quantity of material from said container into said compartment when said container is supported in inverted position, said valve means actuatable by 25 a manual rotary manipulation of the neck of said container, in a direction to open said valve upon screwing on of said cap, and to close the same upon unscrewing of said cap.

EARL F. METCALFE.
